UNITED STATES PATENT OFFICE

118,054

DESIGN FOR A SPRAY BOOTH

Frederick A. Prahl, Jr., Hamilton, and Charles C. Bell, Marblehead, Mass., assignors to United Shoe Machinery Corporation, Borough of Flemington, N. J., a corporation of New Jersey

Application November 1, 1939, Serial No. 87,999

Term of patent 14 years

To all whom it may concern:

Be it known that we, Frederick A. Prahl, Jr., and Charles C. Bell, citizens of the United States, residing at Hamilton and Marblehead, in the county of Essex and Commonwealth of Massachusetts, respectively, have invented a new, original, and ornamental Design for a Spray Booth, of which the following is a specification, reference being had to the accompanying drawing, forming part thereof.

In the drawing,

Fig. 1 is a perspective view showing the front of the spray booth embodying our new design; and

Fig. 2 is a perspective view showing the rear of the spray booth.

We claim:

The ornamental design for a spray booth, substantially as shown.

FREDERICK A. PRAHL, JR.
CHARLES C. BELL.
